UNITED STATES PATENT OFFICE.

FREDERICK W. CLAYBROOK, OF BALTIMORE, MARYLAND.

NEEDLE ATTACHMENT FOR SOUND-REPRODUCING MACHINES.

1,281,135.

Specification of Letters Patent.

Patented Oct. 8, 1918.

Application filed January 31, 1917. Serial No. 145,652.

To all whom it may concern:

Be it known that I, FREDERICK W. CLAYBROOK, a citizen of the United States, residing at Baltimore, in the State of Maryland, have invented certain new and useful improvements in Needle Attachments for Improvements in Needle Attachments for Sound-Reproducing Machines, of which the following is a specification.

This invention relates to attachments for holding the needle in sound reproducing machines with the object of absorbing the undesirable vibrations due to various causes and which result in harsh grating or screeching sounds; and also of reducing the wearing sounds; and also of reducing the wear 15 on the record disk to a minimum.

As is well known, the channels in the record disk which are produced by the action of the needle in the sound recorder are undulating and vary in depth and steepness 20 with the amplitude and pitch of the sound waves projected upon the diaphragm of the recorder. The needle of the graphophone, phonograph or other reproducing machine following in these grooves or channels, is 25 caused to vibrate in exact unison with the undulations, except for certain undesirable variations hereinafter referred to, and this generally speaking, reproduces the same sounds in the horn or other sound trans-

mitter.

Among the causes which contribute to undesirable sounds which interfere with the transmission of the true sound waves may be mentioned the following: When the undulations in the record channel are formed 35 of gradual curves the needle follows faithfully all of the indentations, but if a very sudden or steep incline is encountered, the needle will be thereby thrown upward with greater rapidity or violence and may be 40 caused to actually leave the record, immediately returning upon the rebound and not only producing a false tone or sound but to a certain extent marring the record, many 45 repetitions of this action resulting in wear and injury.

In order to accurately reproduce the sounds or notes corresponding to the record, the vibrations of the needle must be caused 50 solely by the recorded undulations. Like all bodies that are free to vibrate, the needle has a certain rate of vibrations of its own to which it will respond if that particular note or number of vibrations is impressed 55 upon it. From this it follows that if perchance the needle encounters a certain num-

ber of undulations in the record to which it is attuned, or with which its natural vibrations are in synchronism, it will add its own vibrations thus produced to those caused by 60 the record, thereby multiplying the amplitude of vibrations of the needle and producing a false note which is recognized as a screeching sound occasionally produced.

Undesirable sounds, such as the harsh 65 grating sounds, are produced by the imperfections in old or worn-out records. Foreign substances, such as particles of dust, encountered by the needle also produce false and undue vibrations which result in im- 70 proper sounds.

Certain of the causes above mentioned have been heretofore known and various attempts have been made to overcome the defects. Thus it has been proposed to surround the needle with a rubber sleeve and to interpose a rubber disk or block or a spiral spring between the needle and the sound-box in the endeavor to absorb undue vibrations; and also to remove the dust particles 80 from the record by means of a separate brush holder clamped to the shank of the usual needle holder or to the casing of the sound-box. Instead of analyzing the deficiencies of such prior devices it is deemed 85 sufficient to hereinafter point out the requirements and the manner in which I have embodied them in the device disclosed herein.

In the accompanying drawings, Figure 1 90 is a side elevation of the usual sound box and needle holder of a phonograph together with a sectional view of a device embodying the features of my invention; Fig. 2 95 is a top plan view of my device; and Fig. 3 95 is an end view of the same showing the attachment of the brush.

In the drawings, I have shown conventionally the outer end 2 of the tone-arm, having pivoted thereto the sound-box tube 100 3, carrying the reproducer or sound-box 4 which is provided with usual diaphragm 6, to which is attached the arm 7, connected to the plate 8, carrying the needle-socket 10.

My needle-carrying attachment for absorbing false vibrations and accurately transmitting the true vibrations corresponding with the undulations in the record comprises a main supporting member 15 which may be constructed of brass or other suitable material, and is provided at one end 110 with a socket having a contour correspond-

ing to the end of the needle-socket 10, and through which projects the supporting pin 17, riveted or otherwise rigidly attached thereto, this pin being inserted into the 5 socket provided for the needle. A pad of felt or the like 18 is interposed between the end of the socket member 10 and the bottom of the recess in the attachment 15.

A resilient member 20, preferably consisting 10 of a flat stiff steel band forming a leaf spring slightly curved in section as indicated and surrounded or incased in a sleeve of felt or the like 21, is clamped at one end in a recess in the lower side of the member 15, and at its other free end in a recess in the needle-socket member 23 of my device, being made fast by the rivets 24 and 25.

The needle 30, is received in a hole passing 20 through the member 23 and may be adjusted therein as desired to vary the strength of tone, and then secured by the set screw 31. In case the upper end of the needle projects it is prevented from ever contacting with the metal of the member 15 by the 25 felt strip 19 attached to the lower side.

The parts are so arranged that the needle aperture in the lower member 23 has the same angle of inclination as the needle socket in the member 10. This is necessary 30 because it is essential that the predetermined proper angle which the needle makes with the record disk 35 shall remain unaltered.

It is necessary that the vibrations of the needle shall be in the vertical plane passing 35 through the needle 30 and the pin 17, and for this reason I provide a flat or leaf spring which is rigidly clamped at its ends in the members 15 and 23, and is of sufficient width to resist any sidewise or any lateral 40 torsional or tilting movements. The needle is, therefore, compelled to vibrate in a vertical plane, and the device as an entirety transmits the thrusts imparted by the undulatory record path in alignment with the 45 arm 7.

While the leaf spring 20 is sufficiently stiff to serve as a rigid connecting portion between the members 23 and 15, as regards all legitimate undulations in the record 50 disk, yet it is sufficiently resilient to absorb unusual vibrations caused by the imperfections of worn records, and the tendency to a sudden and unnatural increase in the amplitude of vibrations caused by a tendency 55 to rebound from a very steeply inclined undulation, or an overtone or harmonic due to record undulations producing vibrations in synchronism or attuned to the natural note of vibration of the needle itself. These 60 superinduced vibrations are definitely absorbed by the molecular structure of the metal leaf spring surrounded by the deadening envelop of felt, so that substantially nothing but the fundamental or true record

vibration is transmitted by the attachment 65 as an entity to the arm 7 of the sound-box. These characteristics of my device due to the rigid yet resilient leaf spring connector 20, are not true of devices which relay upon an interposed rubber pad or spiral spring which 70 necessarily yields more or less in all directions and does not possess the requisite rigidity to accurately transmit the fundamental record vibrations. In my device the deadening and absorption of false vibrations or 75 noises is apparently perfect and I attribute this to the fact that the resilient metal connector 20 is completely insulated from metallic contact with the members 15 and 23 by the felt-like envelop 21.

I have previously referred to the false sounds produced by a particle of dust or other foreign substance engaging the needle. It has been proposed to provide a separate attachment carrying a brush. To efficiently 85 perform its function it should be adjacent the needle but should not interfere with the functioning of the shock-absorbing medium. I therefore provide a transverse slot in the leading end of the member 15, into which 90 is inserted the back 27 carrying the brush portion 28. Inasmuch as it is necessary to renew the brush occasionally I prefer to make the back 27 and slot wedge-shaped, the parts fitting tightly yet permitting the 95 brush to be detached.

I have described in detail the construction illustrated in the accompanying drawing for the purpose of disclosing an embodiment of my invention but it will be evident to engineers that various changes and modifications may be made within the scope of my claims and without departing from my invention. I have specified certain materials for the different parts but other materials 105 may be employed which produce the same result in substantially the same manner.

I claim:

1. A holder for sound reproducing needles, comprising a supporting member and a needle clamping member, a connector having its ends secured respectively to said members, said connector comprising a spring plate resilient in the vertical plane of the needle but non-resilient in a plane transverse thereto, and cushioning media interposed between the connector and said members.

2. A holder for sound reproducing needles, comprising a supporting member having a pin adapted to enter the needle-socket of a sound reproducing machine, a leaf spring secured to said member at one end to yield in the vertical plane of said pin, a needle clamping member carried by the opposite end of said spring and having a needle socket having the same angle of inclination as said pin, and cushioning

media interposed between the ends of the
spring and said members.

3. A holder for sound reproducing
needles, comprising a supporting member
5 having means for attachment to the needle
socket of a sound reproducing machine at the
one end thereof and brushing means at the
opposite end, a needle clamping member
having a socket to receive a needle, and a
10 spring plate connecting said members which

is yieldable in the vertical plane of said
needle and non-yieldable in other planes.

4. A holder for sound reproducing
needles as set forth in claim 3, wherein said
brushing means is detachably secured to said 15
supporting member.

In testimony whereof I affix my signature.

FREDERICK W. CLAYBROOK.
